Primary Examiner — Melody N Brown*(74) Attorney, Agent, or Firm* — Plumsea Law Group, LLC(57) **CLAIM**

The ornamental design for a steering wheel for automobile, as shown and described.

DESCRIPTION

FIG. 1 is a right, front perspective view of a steering wheel for automobile showing my new design;

FIG. 2 is a right, rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines shown in the drawings illustrate portions of the steering wheel for automobile that form no part of the claimed design.
